UNITED STATES PATENT OFFICE.

JOSEPH DENNIS, OF ROANOKE, VIRGINIA, ASSIGNOR OF ONE-HALF TO JAMES E. UQUHART, OF ROANOKE, VIRGINIA.

TRACK-SANDER.

1,160,147.

Specification of Letters Patent.

Patented Nov. 16, 1915.

Application filed March 4, 1915. Serial No. 12,022.

To all whom it may concern:

Be it known that I, JOSEPH DENNIS, a citizen of the United States, residing at Roanoke, in the county of Roanoke and 5 State of Virginia, have invented certain new and useful Improvements in Track-Sanders; and I do declare the following to be a full, clear, and exact description of the invention, such as will enable others skilled 10 in the art to which it appertains to make and use the same.

My invention relates to improvements in track sanding devices and more particularly to those used on locomotives, such devices 15 usually including a sand dome disposed upon the boiler, whereby the sand is maintained in a very dry state, for facilitating its delivery from the dome to the rails.

Heretofore, numerous devices have been 20 provided for discharging the sand from the dome, and most of these devices employ complicated systems of valves and levers. Needless to say, complete simplicity in a 25 device of this character, is therefore a great advantage. It is to attain such simple means for discharging the sand from the dome, that I have provided the novel construction hereinafter described and claimed.

In describing the invention, I shall refer 30 to the accompanying drawings wherein like reference characters designate corresponding parts throughout the various figures and wherein:

Figure 1 is a horizontal section of a sand 35 dome provided with delivery means, constructed in accordance with the invention; and Fig. 2 is a section cut diametrically through the dome, this view being taken upon the plane indicated by the line 2—2 40 of Fig. 1.

In these drawings, constituting a part of 45 the application, 1 designates a common type of sand dome which is provided with a solid bottom 2 from which an annular flange 3 depends, said flange being shaped to fit the shell of the boiler B as indicated in Fig. 2.

Depending from the bottom 2, at diametrically spaced points, is a pair of sand delivery chutes 4 into the upper ends of which these openings 5 discharge. Anchored within these openings 5 and rising therefrom into the dome 1, are the long arms 6 of a pair of inverted U-tubes 7, the short arms 8 55 of which are provided on their lower ends

with Venturi tubes 9, the latter opening downwardly and being spaced above additional openings 10 which are spaced inwardly from the openings 5.

Disposed between the boiler B and the bottom 2, is a pipe 11 to which compressed air is fed by a supply pipe 12 leading to one outlet of a multiple port valve 13, pressure being delivered to said valve by a main air supply pipe 14 which may lead to any 60 appropriate source of fluid pressure. Connected to and rising from the opposite ends of the pipe 11 through the openings 10, is a pair of upright blow pipes 15 having centrally perforated caps 16 on their upper 70 ends. These caps are so disposed beneath the Venturi tubes 9 as to cause air forced into said tubes by said pipes, to draw sand from the dome or tank and deliver it into the chutes 4 as will be obvious by an inspection of the drawings. 75

It will be understood that any appropriate sanding pipes are adapted to lead from the lower ends of the chutes 4 to the tracks or to individual sanding pipes, and 80 that in order to facilitate the passage of the sand through such a system of pipes, it is expedient to provide means subordinate to the U-tubes 7. For this purpose, I have provided a pair of upright blow pipes 17 85 leading through bosses 18 into the upper sides of the chutes 4, said pipes 17 being connected to the opposite ends of a U-shaped pipe 19 to which compressed air is supplied by a pipe 20 leading from one of 90 the outlets of the valve 13.

By the construction above described, the multiple port valve 13 may be so actuated as to first admit compressed air only into the pipes 20, 19 and 17, thus effectively cleaning the chutes 4 and pipes leading therefrom of any sand which might have lodged therein. Manipulation of the valve to another position, will now not only allow compressed air to be forced through the aforesaid pipes, but through the pipes 12 and 11, thereby delivering sand through the U-tubes 7 to the chutes 4, in which chutes the sand is acted upon by the blasts of air directed downwardly from the blow pipes 17, whereby it is effectively blown upon the track. 100

It is to be observed that considerable space prevails between the bottom 2 and the boiler B and that the compressed air pipe 11 and a portion of the pipe 12, are disposed with- 110

in this space. This is essential since heat from the boiler accumulates within the flange 3 beneath the bottom 2, thus not only effectively drying the sand in the dome, but heating the compressed air as it is discharged through the pipes 12 and 11. By so doing, more expansive power and more force is imparted to said air, thus allowing the sand to be more readily discharged. It will be understood, however, that the moment the supply of air is checked, no more sand will be discharged from the tank.

It is to be noted, that by the construction and arrangement of parts above described, no parts are disposed within the dome or tank 1, with the exception of the tubes 7 and the elements adjacent thereto. This is very important, since it is undoubtedly advantageous to have the greater portion of the tank free from internal obstructions.

From the foregoing description, taken in connection with the accompanying drawings, it will be evident that although very simple construction has been provided for carrying out the object of the invention, the complete device will be very efficient in operation and will possess a number of advantageous features.

I claim:

1. The combination with a sand dome having a pair of openings in its bottom, of

an inverted U-tube in the tank, and having a long arm anchored in one of the openings, and a short arm disposed above the other opening, a Venturi tube carried by the lower end of said short arm, and a blow pipe rising through the last named opening and discharging into said Venturi tube.

2. The combination with a sand dome, of an upright blow pipe rising through the bottom thereof and terminating adjacent said bottom, a downwardly opening Venturi tube disposed over said pipe, and a delivery tube leading from said Venturi tube to the exterior of the dome.

3. The combination with a sand dome adapted to be supported above a locomotive boiler, of a blow pipe rising through the bottom of said tank, a fluid pressure supply pipe disposed beneath said bottom and delivering into said blow pipe; a Venturi tube disposed within the bottom at a point above said blow pipe, and a delivery tube leading from the Venturi tube to the exterior of the tank.

In testimony whereof I have hereunto set my hand in presence of two subscribing witnesses,

JOSEPH DENNIS.
